UNITED STATES PATENT OFFICE

2,525,209

TOILET CASE

Luther C. Davis, Thomaston, Ga.

Application July 3, 1947, Serial No. 758,774

5 Claims. (Cl. 15—203)

1

This invention relates to new and useful improvements in toilet cases, and more particularly to combination brush, comb and mirror sets.

The primary object of the present invention is to provide a case including a plurality of pivotal bristle-holding members and novel and improved means for simultaneously raising all of said members whereby the bristles carried thereby will be extended from the case for use.

Another important object of the present invention is to provide a toilet case including a removable outer cover highly polished to provide a mirror and so designed as to permit the same to engage a pocket or other suitable supporting element for suspending the article therefrom for use.

A further object of the present invention is to provide a toilet set having the foregoing purposes and including means whereby the bristle-holding members may be locked in an extended position for use.

A still further aim of the present invention is to provide a combination brush, comb and mirror set that is simple and practical in construction, strong and reliable in use, relatively inexpensive to manufacture, neat and attractive in appearance, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a group perspective view showing the outer case applied to the inner case with dotted lines showing the outer case removed from the inner case;

Figure 2 is a side elevational view of the inner case with parts broken away and shown in section, and showing the bristle holding members in an inclined position;

Figure 3 is a view similar to Figure 2 and showing the bristle holding members in a slightly raised or extended position;

Figure 4 is a view similar to Figure 2 and showing the bristle holding members in a locked extended position;

Figure 5 is a top plan view of Figure 4;

Figure 6 is a fragmentary perspective view of one corner of the inner case and showing the

2

bristle holding members in a locked extended position;

Figure 7 is a group perspective view of the inner case and parts carried thereby;

5 Figure 8 is a transverse vertical sectional view taken substantially on the plane of section line 8—8 of Figure 6; and

Figure 9 is a perspective view of the outer case.

Referring now to the drawings in detail where-
10 in, for the purpose of illustration, there is dis-
closed a preferred embodiment of the present
invention, the numeral 18 represents the inner
case generally formed from a single sheet of
substantially rectangular material 12 having its
15 longitudinal side edges turned upwardly to pro-
vide flange portions 13 and 14, for the purpose
of clarity in the description. One of these
flanges is designated as a forward flange 13 and
the other flange a rear flange 14. Adjacent the
20 transverse edges of the sheet 12 are provided
ribs 16 integrally formed with the sheet.

The numeral 18 represents generally a plural-
ity of bristle-holding members comprising elon-
gated strips of metal each folded longitudinally
25 upon itself to provide juxtaposed plates 20 and
22.

Adjacent upper and lower hollow protuber-
ances 24 and 26 are provided in the transverse
edges of these plates to engage upper members
30 and lower members 30.

Extending through transversely spaced aper-
tured 32 in the ribs 16 are nails or the like 34
that pivotally engage the lower members 30 car-
ried by the adjacent protuberances 26. Extend-
35 ing transversely between the upper members 28
are connector bars 36 that are pivotally secured
to the upper members 28 by nails or pivot pins 38.

Pivotally mounted to the bars 36 at one termi-
nal portion are the outwardly turned arcuate
40 ends 40 of a U-shaped locking member 42 that
engages the flanged portion 14 of the inner case.

Adjacent, longitudinally spaced, hollow pro-
tuberances are provided at one edge of the plates
20 and 22 and receive groups of bristles 46, the
45 free ends of which project well outwardly from
said plates.

The numeral 48 designates generally the outer
case or cover, formed of a highly polished
metal so that the same will constitute a mirror.
This cover is formed from a rectangular strip

of metal bent substantially U-shaped and having its terminal portions turned inwardly to provide retainer flanges 50 and 52 that bear against the outer, undisturbed face of the inner case. One of these flanges, for example 50, is preferably of an increased width with respect to flange 52 and is turned slightly outwardly to facilitate the same to clampingly engage a pocket when the device is being carried or some suitable supporting element for use of the outer cover as a mirror.

When the cover is applied to the inner case, as shown in Figure 1, the plates 20 and 22 are inclined forwardly toward flange 13 against each other and overlie a comb 54 placed between flange 13 and the adjacent strip 18.

To extend the strips 18 at right angles with the case 12 and the bristles 46 outwardly of the inner case, it is merely necessary to remove the outer case 48, pull outwardly and rearwardly upon member 42 and engage the same with flange 14, as shown in Figure 4 of the drawings with the arcuate ends or terminal hooks 40 of the member 42 engaged over the outer edge of the flange 14.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A toilet article comprising a base, spaced parallel ribs integrally formed with said base, a plurality of elongated strips folded longitudinally upon themselves to provide juxtaposed plates, adjacent upper and lower protuberances provided in the transverse edges of said plates, upper and lower members fixed in said upper and lower protuberances, means pivotally securing said lower members to said ribs, connecting bars pivoted to said upper members, a substantially U-shaped locking member having terminal hooks pivoted to said connecting bars, means carried by said base engageable with the terminal hooks of said locking member to retain said plates disposed substantially perpendicular to said base, and groups of bristles fixed between said plates and projecting outwardly therefrom.

2. A toilet article comprising a base, spaced parallel ribs integrally formed with said base, a plurality of elongated strips folded longitudinally upon themselves to provide juxtaposed plates,

adjacent upper and lower protuberances provided in the transverse edges of said plates, upper and lower members fixed in said upper and lower protuberances, means pivotally securing said lower members to said ribs, connecting bars pivoted to said upper members, a substantially U-shaped locking member having terminal hooks pivoted to said connecting bars, means carried by said base engageable with the terminal hooks of said locking member to retain said plates disposed substantially perpendicular to said base, adjacent, longitudinally spaced, hollow protuberances provided in the free edges of said plates, and groups of bristles mounted in said hollow protuberances and having free ends projecting outwardly from said plates.

3. The combination of claim 1 wherein said means carried by said base engageable with the terminal hooks of said locking member includes an upstanding flange.

4. The combination of claim 1 and a substantially U-shaped cover having its terminal portions turned inwardly to provide retainer flanges, said retainer flanges of said cover yieldingly bearing upon the said base.

5. A toilet article comprising a substantially rectangular inner case having its longitudinal edges turned upwardly to provide a pair of spaced flanges, a pair of space parallel ribs integrally formed with said inner case, a plurality of spaced parallel bristle holding members pivoted to said ribs, links pivotally connecting said members to each other, a substantially U-shaped locking member having terminal hooks pivoted to said links, said terminal hooks engageable with one flange of said inner case to retain the members in a raised position, and an outer substantially U-shaped case having its terminal portions turned inwardly to provide retainer flanges yieldingly bearing upon said inner case, the web portion of said outer case extending transversely between the flanges of said inner case, and the leg portions of said U-shaped outer case defining end walls extending transversely between the ends of said flanges.
